BATTERY HAND LAMP

Charles A. Gillingham, Lakewood, Ohio, assignor to National Carbon Company, Inc., a Corporation of New York

Application July 12, 1930. Serial No. 467,568

6 Claims. (Cl. 240—10.65)

My invention relates to a unitary battery hand lamp having a non-refillable casing.

Lamps of this type that have been made heretofore have been so constructed that some 5 of the parts could be renewed by the user. Such replaceable elements have involved details of construction that have tended to increase the cost of manufacture or the weight, size and attractiveness of the lamp.

10 One of the objects of my invention is to make a lamp of simple construction at a relatively low cost.

Another object of my invention is to make a small attractive lamp which is serviceable 15 and may be conveniently carried and operated.

Another object of my invention is to construct a battery hand lamp at such a low cost that it can be economically discarded after the battery has been discharged.

20 Another object of my invention is to construct a battery hand lamp having all of its parts permanently secured in place and enclosed in a non-refillable casing.

The above and other objects of my invention 25 will be more clearly understood from the following description and accompanying drawing; in which,

Fig. I is a vertical section of the battery hand lamp showing the interior of the lamp in elevation.

30 Figs. II and III, respectively, are top and bottom plan views of the battery hand lamp.

Fig. IV is a top view of the lamp with the top cover removed.

35 Fig. V is a development of an insulating strip used in the head of the lamp.

To illustrate my invention, I have shown a battery comprising a pair of dry cells 1 arranged in parallel relation to each other. The cells 40 shown herein are the round type cell having a negative cup electrode 2 and a positive rod electrode 3 projecting from the top of the cup 2. The cells are separated by a short spacer 4 which is interposed between the two cells 45 and forms in combination therewith a recess 5 at the top of the battery. Preferably, this spacer 4 is made of wood or other insulating material but the cells may be insulated from each other by providing at least one of the cells 50 with an insulative tubular covering such as is commonly employed to cover unit cells of this type. The ends of the cells are reversed with respect to each other which places the positive electrode 3 of each cell at the opposite 55 end of the battery. The bottom of the cup

electrode 2 is connected to one of the positive electrodes 3 at the bottom of the battery by an electrical conducting strip 6 which passes across the bottom end of the battery.

An electric light bulb 7 fits into the recess 5 at the top of the battery. The central terminal 8 of the bulb 7 is connected to the positive terminal 9 of the battery by a Z shaped electrical conductor 10 having one end connected to the positive terminal 3 of the cell at the top of the battery and having the other end extending into the recess 5 and forming a contact with the central bulb terminal 8. The Z shaped conductor 10 is insulated from the cells and the electric light bulb 7 by an insulating strip 11, the development of which is shown in Fig. 5. The strip 11 is bent on the dotted lines 12 indicated in Fig. V in order that it may extend underneath the Z shaped conductor and pass down on one side of the recess 5 across the bottom and upwardly along the other side of the recess. A flap 13 is provided on the insulating strip 11 which is folded on the dotted line 14 in Fig. V so that it may extend over the Z shaped conductor 10, for the purpose of insulating the outside terminal 15 of the electric light bulb 7 from the conductor 10. The battery circuit may be completed through the electric light bulb 7 by a leaf spring switch 16 which has one end connected to the negative terminal 17 of the battery and has the other end positioned adjacent to but out of contact with the outside terminal 15 of the electric light bulb.

In order to securely bind the cells 1 together and to form a good electrical connection between the unlike poles of the cells it is desirable to solder the points of contacts between the conductors 6, 10 and 16 and the electrodes 2 and 3. It is also desirable to solder the central terminal 8 of the electric light bulb 7 to the Z shaped conductor 10.

A flexible cover 18 preferably of insulating material comprising a thick inner layer 19 of material and a thinner outer layer 20 of material is wound around the battery assembly and the edges of the cover are cemented together along a vertical seam 20a. A piece of cardboard 21 or other piece of stiff sheet material having the shape of the bottom contour of the battery is placed over the bottom of the battery. The bottom edge of the thinner layer 20 of covering material projects beyond the bottom of the battery and it is folded over the bottom cardboard 21 and the edges of the folds 22 are cemented together.

A stiff top cover 23 of insulating material is placed over the top of the battery and it is provided with an aperture 24, the inner edges of which rest against the top of the electric light bulb 7. The edges of the top cover 23 are cemented to the top end of the flexible cover 18 and a strip 25 having an aperture 26 therein is cemented over the top cover and to the sides of the flexible cover so that the aperture 26 in the strip coincides with the aperture 24 in the top cover.

The battery may be operated by pressing the flexible cover 18 at the top of the spacer 4 immediately over the end of the leaf spring switch 16 at the point indicated by the arrow. This point may be visually indicated by suitable lettering and it may be detected by the touch, by forming a rise or a depression at this point. The switch is actuated to form a contact between the outer terminal 15 of the electric light bulb and the negative terminal 17 of the battery to complete the battery circuit and the light is projected through the aperture provided in the top cover of the battery.

25 I claim:

1. A battery hand lamp comprising a dry battery formed of a pair of dry cells having their unlike electrode terminals disposed at the opposite ends of said battery; a short spacer separating said cells and providing a space at one end of said batteries between said cells; an electric light bulb in said space and having one of its terminals electrically connected to one terminal of said battery; a switch electrically connected to the other terminal of said battery and adapted to be actuated to form a contact with the other terminal of said bulb; and a casing enclosing all of said elements, said casing comprising a flexible side adapted to be pressed to actuate said switch.

40 2. A battery hand lamp comprising a dry battery formed of a pair of parallel dry cells having their unlike electrode terminals disposed at opposite ends of said battery; an electrical connection between the unlike terminals at one end of said battery; a short spacer separating said cells and providing a recess between said cells at the other end of said battery; a Z shaped electrical conductor having one end connected to one terminal of said battery and the other end terminating in said recess; an electric light bulb positioned in said recess and having one of its terminals in contact with said Z conductor; an insulating strip extending along the bottom and side walls of said recess and interposed between said conductor and the exterior walls of said cell; a switch connected to the other terminal of said battery and adapted to form a contact with the

other terminal of said bulb; and a flexible casing for the battery sides and an end cover having an aperture therein against the inner edge of which the outer end of said bulb abuts.

3. A battery hand lamp comprising a dry battery formed of a pair of parallel dry cells having their unlike electrode terminals disposed at opposite ends of said battery; an electrical connection between the unlike terminals at one end of said battery; a short spacer separating said cells and providing a recess between said cells at the other end of said battery; a Z shaped electrical conductor having one end connected to one terminal of said battery and the other end terminating in said recess; an electric light bulb positioned in said recess and having one of its terminals in contact with said Z conductor; a switch connected to the other terminal of said battery and adapted to form a contact with the other terminal of said bulb; and a flexible casing for the battery sides and an end cover having an aperture therein against the inner edge of which the outer end of said bulb abuts.

4. A battery hand lamp comprising a dry battery; an electric light bulb adapted to be placed in circuit with said battery; a switch for completing said circuit, and a non-removable casing enclosing all of said elements comprising a stiff top end cover having a hole therein, one edge of which fits against said bulb, a bottom end cover, and a flexible side cover wrapped around said battery and secured to said end covers, said side cover being adapted to be flexed to actuate said switch.

5. A battery hand lamp comprising a battery of dry cells; an electric light bulb having one of its terminals connected to one of the battery terminals; a switch connected to the other battery terminal; a casing having end covers and a flexible side cover wrapped around said battery and secured to said end covers, and said side cover being adapted to be pressed to move said switch in contact with the other terminal of said bulb.

6. A battery hand lamp comprising a battery of dry cells having their axes parallel to each other; a spacer separating said cells; an electric light bulb supported on said spacer and protected by the ends of said cells; a conductor connected to one terminal of said battery and to one terminal of said bulb; a switch connected to the other terminal of said battery; a casing enclosing all of said elements, said casing having a flexible side cover wrapped around said battery and adapted to be pressed to actuate said switch.
